INTERNAL-COMBUSTION ENGINE

Karl K. Probst, Lansing, Mich.

Application October 15, 1945, Serial No. 622,261

5 Claims. (Cl. 123—71)

1

This invention relates to internal combustion engines, and particularly to those of the two-cycle type, the principal object being the provision of an engine of this type that is efficient and economical in operation.

Objects of the invention include the provision of a two-cycle engine in which a positive charge of combustion supporting air, either carbureted or uncarbureted, is admitted to each cylinder each time the corresponding piston approaches its bottom dead-center position; the provision of internal combustion engines of the two-cycle type in which the air discharged to the cylinders is discharged under a much greater pressure than in base compression types of constructions; the provision of a two-cycle engine having an exhaust and an intake port in a wall thereof at least partially controlled by movement of the corresponding piston and in which it is possible to positively supercharge the engine; the provision of a two-cycle engine having a novel timing of the ports thereof; the provision of a two-cycle engine of the differential piston type in which the larger portion of each piston acts to positively pump the air required for supporting combustion in the corresponding cylinder; the provision of an engine of the type above described in which a rotary valve is provided for controlling the passage of the air pumped by the larger diameter portion of the piston to the engine power cylinder; the provision of a construction as above described in which the rotary valve not only serves to aid in the control of the passage of such air to the combustion chamber, but serves as a temporary storage chamber for the air so compressed; the provision of a construction as above described in which the rotary valve, in a multi-cylindered engine, individually stores the air pumped by each piston for use in the corresponding cylinder; and the provision of a two-cycle engine having a rotary valve for controlling passage of air to the engine cylinders for supporting combustion therein, which operates at only a fraction of the crank shaft speed.

The above being among the objects of the present invention, the same consists in certain new and novel features of construction and combinations of the parts to be hereinafter described with reference to the accompanying drawings, and then claimed, having the above and other objects in view.

In the accompanying drawings which illustrate a suitable embodiment of the present invention and in which like numerals refer to like parts throughout the several different views,

2

Fig. 1 is a partially broken, partially sectioned, side elevational view of a two cylinder, two-cycle engine embodying the present invention.

Fig. 2 is a transverse, vertical sectional view of the engine shown in Fig. 1, taken as on the line 2—2 thereof.

Fig. 3 is a fragmentary transverse sectional view taken on the line 3—3 of Fig. 1 in the plane of the passage connecting the carburetor with

10 the pumping cylinder.

Figs. 4, 5, 6, and 7 are more or less diagrammatic views illustrating the valve for controlling the various functions of the engine in cross section corresponding in each case with the various passages in the engine for controlling the flow of gases therein and the relation of the passages in the valve to the corresponding positions of the piston in the cylinder.

Fig. 8 is a side elevational view of the rotary 20 valve employed in the engine shown in the preceding views.

Figs. 9, 10, and 11 are transverse, sectional views of the valve shown in Fig. 8, taken, respectively, on the lines 9—9, 10—10, and 11—11 of Fig. 8, and

25 Fig. 12 is a port diagram for the engine shown in the preceding views.

It is generally understood that two-cycle engines, as compared to four-cycle engines, have the advantage of much greater simplicity in construction and economy in manufacture, but have the disadvantage of lesser flexibility and poorer fuel economy. The present invention has for its principal object the provision of a two-cycle engine retaining the advantages thereof as far as 30 simplicity in construction and economy in manufacture are concerned, but capable of flexibility and fuel economy approaching, if not equaling, that of a four-cycle engine. Briefly, it may be stated that these advantages are obtained by 35 eliminating base compression and employing a differential piston for each cylinder for delivering to the power cylinder portion thereof the charge of air necessary to support combustion, and by providing a rotary valve which, in conjunction with the piston controlling the port of 40 each cylinder, controls the delivery of such combustion supporting the air to the power cylinder. The rotary valve, in accordance with the present invention, not only aids in controlling the admission of the combustion supporting air to each 45 power cylinder of the engine but additionally serves as a storage chamber for the air compressed by each differential piston in the corresponding pumping cylinder of the engine between the time such charge is fully compressed

and the time it is desired to introduce it into the power cylinder. In this last connection, it will be understood that in accordance with the present invention the valve is so formed that when applied to a multi-cylinder engine the charge of air compressed by each piston is delivered only to the power cylinder in which such piston operates, rather than delivery to a storage chamber common to all of the cylinders, this feature resulting in a higher initial pressure of such combustion supporting air at the moment it is initially introduced to its power cylinder, permitting the charge to be introduced into the power cylinder in a shorter length of time than otherwise and providing for improved performance in control. Furthermore, this feature lends itself to a piston controlled cylinder porting by means of which a positive supercharging of the engine may be provided.

Additionally, in the interest of long wear and greater life, the rotary valve is driven at only a fraction of the crankshaft speed, preferably one-half such speed. While rotary valves employed in four-cycle engines are naturally driven at half-engine speed, this feature has been an inherent result of the four-cycle principle and in such case each port in the valve registers with the corresponding port in the cylinder as often as explosions occur in the corresponding cylinder, while in the present case a double set of ports are provided in the rotary valve for each cylinder which alternately align themselves with passages in the cylinder so that each port provides a passage for the flow of gases corresponding with every other explosion in the corresponding cylinder. By this means the speed of the rotary valve is reduced to such extent, as compared to the speed of the crankshaft, as to prevent it from presenting any unusual cooling problems, and at the same time materially increasing its length of life as compared to the life it would have if run at crankshaft speed.

It will, of course, be appreciated that the engine constructed in accordance with the present invention may carburete the air employed for supporting combustion in the engine cylinder in any suitable manner. In other words, the air may be carbureted before being introduced into the engine, as by a carburetor, not until it has been introduced into the power cylinder of the engine, as by fuel injection, or at any suitable point in the path of flow of the air from the intake port in the engine to the power cylinder by any means whatsoever. As a matter of illustration, it is assumed in the particular embodiment illustrated in the drawings by way of illustration that the air is carbureted in the first described manner, namely, by passing through a carburetor of conventional construction before being introduced into the engine. It will also be understood that the present invention is applicable to engines having one cylinder or any number of cylinders, the particular engine shown in the drawing by way of illustration being shown as having two cylinders. Furthermore, it will be understood that the engine of the present invention may be cooled in any suitable way, whether by air, water, or other fluid medium. The engine shown in the accompanying drawings by way of illustration is of the air-cooled type.

Referring now to the accompanying drawings and particularly to Figs. 1 and 2, the engine there shown comprises a crankcase 20 of cast construction with which is integrally formed

two upwardly projecting parallel cylinders indicated generally at 22, each of which is provided with an integral cylinder head portion each of which receives a spark-plug 24 in the conventional manner. Cooling fins 26 are formed integrally with each cylinder 22. The lower open face of the crankcase 20 is closed by an oil pan 28 which is generally of the nature of the oil pans conventionally employed in connection with four-cycle engines, this being differentiated from the conventional type of two-cycle engines employing base compression in which the lower and upper halves of the base are made to relatively closely conform to the area swept by the big ends of the connecting rods and the crankshaft throws. As will be appreciated, the construction shown lends itself to the same type of oiling system as is conventionally employed in four-cycle engines and it is assumed that the engine shown is so equipped.

The crank case 20 carries bearings 30, shown as three in number, which support the two-throw crankshaft 32, the throws of which are angularly spaced from one another by 180°. Each of the throws of the crankshaft rotatably receives thereon the big end of the corresponding connecting rod 34, the upper end of the connecting rods being connected to their corresponding pistons which will now be explained. A flywheel 36 is secured to the rear end of the crankshaft 32 and carries a centrifugal fan 38 which draws air through the sheet metal housing 39 surrounding the cylinders 22 in order to cool the latter.

Referring now particularly to Fig. 2, it will be noted that each cylinder 22 is bored to provide an outer cylindrical portion 40 and a concentric inner cylindrical portion 42 of greater diameter. For the sake of convenience, the portion 40 will hereinafter be referred to as the outer, power or working cylinder and the portion 42 as the inner or pumping cylinder. A differential piston indicated generally at 44 is received in each cylinder 22 and each comprises an outer portion 46 relatively closely, but slidably fitting the bore of the working cylinder 40 in accordance with conventional practice and an inner portion 48 relatively closely, but slidably fitting the bore of the inner cylinder 42, the two portions 46 and 48 being formed integrally with one another and the corresponding connecting rod 34 being connected to the smaller portion 46 in each case by means of a conventional piston pin 50. The lengths of the connecting rods are such in relation to the lengths of the pistons that a minimum of clearance is provided above the pumping piston at upper dead center position.

The head of the working piston 46 is shown as being provided with a conventional deflector or baffle 52 for directing the incoming charge of air upwardly into the cylinder 40 in accordance with conventional practice, but it will be understood in this respect that the head of such piston may vary considerably in conformation depending on the flow characteristics of the gases to and from the working cylinders as will be readily appreciated by those skilled in the art. Also, in the particular embodiment shown, the outer end of each working cylinder 40 is shown as beveled off as at 54 on the side of the piston opposite the baffle 52, but here again the shape of the outer end of the cylinder, which forms the combustion chamber therefor, may vary in each case in accordance with the necessities or desires of the particular designer.

It will, of course, be appreciated that a pumping chamber is created between the upper wall of the pumping piston 48, outwardly of the periphery of the working piston 46 and between the upper face of the pumping piston 48 and the step 56 formed between the working cylinder 40 and the pumping cylinder 42. By varying the relative diameters of the cylinders 40 and 42 and the corresponding piston portions 46 and 48, the effective swept volume of the cylinder 42 may be made to equal that of the cylinder 40, or greater or lesser than the latter. Ordinarily, it will be desirable that the swept volume of the pumping cylinder be somewhat greater than that of the working cylinder in order to make up for any loss in volumetric efficiency of the engine, which loss may result from friction to the flow of gases through the various ports and passages which will hereinafter be described, and for other well known reasons.

Additionally, where maximum power at high engine speeds is particularly desirable at the possible risk of less desirable economy at low engine speeds, the relative diameter of the pumping piston 48 with respect to the working piston 40 may be desirably increased to insure better volumetric efficiency of the working cylinder at such high speeds, and if sufficiently increased, a positive supercharging effect may be obtained. In all such matters, of course, the requirements of the particular design being worked upon and the intended application of the final product will control.

The discharge of exhaust gases from the working cylinder 40 is controlled by the piston in accordance with conventional two-cycle practice. In other words, each working cylinder 40 is provided at one side thereof with one or more exhaust ports 52 which are uncovered by the corresponding working piston 46 when the latter approaches its bottom dead-center position, and which ports 52 discharge through a common outlet such as 54 into an exhaust manifold 58, or the exhaust gases may be discharged directly to the air if desired. It may be noted, however, in the case shown and, as particularly brought out in Figs. 3, 4, and 12, each piston 46 will uncover the corresponding exhaust port 42 approximately 45° before bottom dead-center position and will, of course, close it the same number of degrees past bottom dead-center position.

In accordance with the present invention, the control of combustion supporting air to the working cylinder 42 and the discharge therefrom to the working cylinder 40 is controlled by a rotary valve which is indicated generally at 60. In order to mount the valve 60, a hollow boss 62 is formed integrally with both cylinders 22 and extends along one side thereof, as shown, with its axis parallel to the axis of the crankshaft 32. The boss 62 is provided with a cylindrical bore 63, in which the valve 60 is closely but rotatably received. It will be particularly noted from inspection of Fig. 1 that the forward or left-hand end of the boss 62 is outwardly flanged and has secured and sealed thereto a flat, vertically extending plate 64 which is also sealed and secured to the forward end of the crankcase 20 and oil pan 28. The forward end of the valve 60 projects through the plate 64 and receives a gear 66 thereon which is suitably secured thereto against relative rotation. In vertical alignment with the gear 66, the crankshaft 32 is provided with a gear 68 fixed against rotation thereto. The pitch diameter of the gear 68 is half that of the gear 66.

The two gears 66 and 68 are drivingly interconnected by means of an idler gear 70 suitably mounted on a stubshaft 72 carried by the plate 64. All of the aforementioned gears are enclosed by an oilproof sheet metal housing 74 of more or less pan-like construction, the open outwardly flanged margin of which is suitable secured and sealed to the marginal edge portion of the plate 640. The housing 74 is, of course, provided with a suitable opening through which the forward end of the crankshaft 32 projects. It will be appreciated from the foregoing that the valve 60 will be rotated at half the speed of the crankshaft 32. From inspection of Fig. 1, it will also be noted that the rear or right-hand end of the boss 62 is closed by a plug 76 which substantially abuts the rear end of the valve 60.

Referring now to Fig. 8, which is a side elevational view of the valve 60, it will be noted that the valve includes two consecutive axial portions A and B, each of which serves a corresponding cylinder 22 to control the flow of combustion supporting air into the corresponding pumping cylinder 42, and from the corresponding pumping cylinder 42 to the corresponding working cylinder 40. Inasmuch as the portions A and B are identical to each other, except angularly rotated with respect to each other, the construction and function of one will suffice to explain the construction and function of both. Each portion A and B includes a portion 80 which controls the flow of combustion supporting air from the atmosphere to its corresponding pumping cylinder 42, a portion 82 which controls the escape of such combustion supporting air from each pumping cylinder 42, and a portion 84 which controls the flow of such combustion supporting air to the corresponding working cylinder 40. Each portion A and B is formed within the corresponding portions 82 and 84 thereof with an axial bore 86 forming a pocket, such pockets 86 being formed in the particular case shown by drilling the valve 60 from opposite ends thereof and plugging the outer ends of the holes thus formed as by means of plugs 88 to form two axially distinct and separate pockets 86, one for each portion A and B. Circumferential grooves 90 are provided in the valve 60 between each adjacent portion 80, 82, and 84, and sealing rings 92 are received in each groove 90 for cooperation with the bore 63 in order to seal each of said portions against the escape of gas between them.

As brought out in Fig. 3, the boss 62 in transverse alignment with each portion 80 is provided with a radially extending passage 94 which passages are interconnected by a longitudinally extending passage 96 formed in an intake manifold portion 98 which in turn opens into a carburetor 100 which may be of a conventional type. Thus, the carburetor 100 through the passage 96 may supply a combustional mixture to both passages 94. Likewise, each cylinder 22 in transverse alignment with its corresponding valve portions 80 is provided with a passage 102 which connects the bore 63 of the boss 62 with a port 104 opening into the corresponding pumping cylinder 42 on the corresponding side of a plane perpendicular to the axis of rotation of a crankshaft and including the axis of the corresponding cylinder.

As brought out in Fig. 3, each portion 80 of the valve 60, and on diametrically opposite sides thereof, is cut away as at 106 to provide a flow passage or port operable to interconnect the passages 94 and 102 when the valve is within either of two diametrically opposite positions of angular

movement. Each port or passage 106 is of such angular extent in its relation to relative angular positions and extent of the passages 94 and 102 that, as brought out in Figs. 5 and 12, the corresponding passages 94 and 102 will be opened during operation to each other through the then cooperating port or passage 106 when the corresponding crank pin of the crankshaft 32 is approximately 60° past dead center, and will close communication between the corresponding ports 94 and 102 when such corresponding crank pin has passed beyond bottom dead center position by approximately 40°. It will, of course, be understood that during one down stroke of a piston, one of the corresponding ports 106 will control the flow of combustional mixture through the carburetor 100 into the corresponding pumping cylinder 42, while on the next downward stroke of the piston the remaining corresponding port 106 will control such flow.

As best brought out in Fig. 6, each cylinder 22 in line with the corresponding portion 82 of the valve 60, and which is on the opposite side of the central plane above referred to including the axis of each cylinder from the corresponding port 104, is provided with a port 108, similar to the port 104, and which is connected by a passage 110 with the bore 63 of the boss 62. The portion 82 of the corresponding portion A or B of the valve 60 in transverse alignment therewith is provided with a pair of diametrically opposed ports 112 through the wall thereof. The angular extent of the ports 112 in relation to the angular extent of the passages 110 about the axis of rotation of the valve 60, and the relative rotatable position of the valve 60 and crankshaft 32 is such that, as best brought out in Figs. 6 and 12, one of the ports 112 begins to open into its corresponding passage 110 when the corresponding crank pin is approximately 45° past bottom dead center position, and closes such communication when such pin is approximately 10° past dead center position. During the greater part of this time, the piston 48 in the corresponding cylinder 42 is moving outwardly and compressing the charge which it drew into the cylinder 42 on its down stroke, and is compressing such charge into the corresponding pocket 86 of the valve 60. This charge, as will hereinafter be brought out more clearly, is not immediately allowed to escape to the corresponding working cylinder 40, but is compressed and held in such passage 86. Each pocket 86, being of materially smaller volume than the volume in the corresponding cylinder 42 swept by the corresponding piston 48, the charge thus compressed therein is under a material pressure, depending upon the relation of the volume of the pockets 86 as compared to the swept volume of the cylinders 42, but preferably on the order of thirty to forty pounds per square inch. It will be understood in this latter respect that this figure may vary considerably according to the desires of the particular designer and the effect he is attempting to obtain. In any event, it will be appreciated that this pressure is materially greater than is ever obtained in base compression types of two-cycle engines and is one feature by means of which superior operating characteristics are obtainable by the present invention.

It will be appreciated that the reason why the charge compressed by each piston 48 in its corresponding cylinder 42 cannot be immediately transferred from the pocket 86 to the corresponding working cylinder 40 is that such charge is not fully compressed until the piston has reached

its upper dead center position, at which time the explosion occurs in the corresponding working cylinder. Consequently, it is necessary to hold such charge in the corresponding pocket 86 until the corresponding working piston has approached its bottom dead center position and the pressure of the exhaust gases in the cylinder has been materially dissipated.

In order to control the discharge of such compressed gas in each pocket 86 to the corresponding working cylinder 40, each portion 84 of the valve 60 is provided with a pair of diametrically opposed ports 114 therein connecting the corresponding pocket 86 with the periphery of the portion 84. Each working portion 40 of the cylinder 22 is provided with a port 116 connecting the bore of the corresponding cylinder 40 with the bore 63 in which the valve 60 rotates. Now it will be observed from an inspection of Figs. 2 and 7 that the upper edge of the port 116 is above the upper edge of the exhaust port 52 so that the corresponding working piston 46, in descending, will uncover the port 116 before it uncovers the exhaust port 52, and on its up stroke will close the exhaust port 52 before it closes the intake port 116.

It will be appreciated that if the ports 114 were aligned with the ports 116 at the time the corresponding working piston 46 uncovered the corresponding intake port 116, the products of the combustion in the corresponding working cylinder might be under a pressure superior to the pressure of the charge of air or combustible mixture in the corresponding pocket 86, and tend to blow into such pocket. In order to avoid any such occurrence and to insure the pressure of the burned gases in the working cylinder to be largely dissipated at the time the ports 114 become aligned with the intake port 116, the ports 114 are so angularly related to the valve 60 and the crankshaft 32 that the ports 114 do not begin to open to the ports 116 until, as brought out in the timing diagram of Fig. 12, the corresponding crankpin has reached a position of approximately 15° past bottom dead center. It will be appreciated that by this time the pressure of the burned gases in the corresponding working cylinder will have been substantially dissipated through the corresponding exhaust passage 52, and may have even created a partial suction in the working cylinder due to the inertia effect of such exhaust gases passing through the exhaust port.

In the construction as shown the interruption 55 of the alignment of the ports 114 and 116 is not relied upon to cut off communication between each pocket 86 and its corresponding working cylinder 40 as may be arranged if desired. Instead, the corresponding working piston 46 itself is relied upon and employed to shut off communications between each working cylinder 40 and the corresponding pocket 86 as it has been shown that by this means a more effective flow path between each pocket 86 and its corresponding working cylinder results, particularly toward the end of such communication.

One feature which is to be noted from the timing diagram illustrated in Fig. 12 and resulting from the fact that the intake port 116 extends 70 axially outwardly beyond the upper end of the exhaust port 52, a feature contrary to ported cylinder types of two-cycle engines is that the intake port remains open after the exhaust port closes, namely until the corresponding crank has 75 passed approximately 80° beyond bottom dead

center position in the construction shown. This feature, particularly when combined with the construction in which the swept volume of the pumping cylinder 42 is greater than the swept volume of the power or working cylinder 40 will result in a positive supercharging effect for the engine, inasmuch as in such case the charge from the pocket is being delivered to a closed space.

With the above in view and reviewing the sequence of operations as disclosed in the timing diagram in Fig. 12 and in Figs. 4 to 7 inclusive, and having reference to a single cylinder of the engine only for the purpose of simplification in explanation, it will be appreciated that when the crankpin has turned approximately 60° beyond top dead center position, as indicated in Figs. 5 and 12, one of the passages or ports 106 in the portion 80 of the valve 60 establishes communication between the carburetor 100 and the pumping cylinder 42 through the ports or passages 94, 102 and 104. The piston 44 is moving downwardly at this time, thus creating a suction in the pumping cylinder 42 and draws a charge of combustible mixture into the pumping chamber. This communication between the carburetor and the pumping cylinder remains open until the crankpin has passed beyond bottom dead center position, preferably approximately 40° as indicated in the timing diagram of Fig. 12 and in Fig. 5, so as to insure a maximum amount of such combustible mixture being drawn into the pumping chamber, as will readily be appreciated by those skilled in the art. It will also be understood that when the piston has descended sufficiently to bring its corresponding crankpin to a position of approximately 45° from bottom dead center position, as indicated in Figs. 4 and 12, the piston will begin to uncover exhaust port 52 and permit the escape of the burned products of combustion in the power cylinder 40.

Immediately after communication between the carburetor and the pumping chamber is interrupted, as indicated in Figs. 6 and 12, one of the passages 112 in the portion 82 of the valve 60 will open communication through the ports 108 and 110 between the pumping chamber and the pocket 86 in the valve 60, and as the piston 44 continues to rise in the cylinder the charge therein will be compressed and forced into the pocket 86. This action will continue until the crankpin has preferably passed slightly beyond upper dead center position, shown in the timing diagram of Fig. 12 and in Fig. 6 at 10° past top dead center position. This lag in closing is, of course, for the same general reasons as the lag in closing the first mentioned port between the carburetor and the pumping cylinder. The lag in this case does not require to be extended to such a great degree in view of the relatively high pressure on the charge at this time.

When the communication between the pumping chamber and the pocket 86 of the valve 60 closes as above described, the pocket 86 is then charged with substantially the entire volume of the charge of combustible mixture which has been drawn from the carburetor into the pumping chamber and is compressed into a much smaller volume than the swept volume of the pumping chamber. While the pressure of the charge in the pocket 86 may, of course, be varied considerably in design to accord with the desires of the particular designer and the characteristics desired in the ultimate engine, it has been found that a pressure of 30 to 40 pounds per

70 square inch has resulted in very satisfactory operation.

The charge remains compressed in the pocket 86 and, of course, the corresponding passages 114 until, as brought out in Fig. 7 and in the timing diagram of Fig. 12, the crankpin has passed 15° beyond bottom dead center position. This communication between the pocket 86 and the interior of the working cylinder 40 which opens at 10 15° past bottom dead center position continues until the crankpin has turned through an angle of approximately 80° beyond bottom dead center position, at which time it is closed. The closing of this communication may be effected by rotation of the valve 60 so as bring the ports 114 and 116 out of registry with one another but, as previously described, it is preferable to cut off such communication by the piston 44 itself, the upper edge of the port 116 in such case to cut off such communication. By this method of closing off such communication, a maximum amount of area of the port 116 remains open until the last moment and is important inasmuch as at the time such port is closed the pressure of the gases in the pocket 86 has dropped to a minimum amount, the value of which will depend upon the ratio of the swept volumes of the cylinders 40 and 42. Furthermore, because the pressure of exhaust gases in the working cylinder 40 has dropped to approximately zero at the time the pocket 86 is communicated with such cylinder, and because the charge in the pocket is under a material positive pressure, such charge will flow quickly and easily into the power cylinder. Additionally, because the exhaust gases have largely been cleared from the power cylinder when the charge from the pocket 86 is introduced into it, a minimum of dilution of such charge by exhaust gases 40 will occur.

It is important to note that although the intake port into the power cylinder is initially open at the same time that the exhaust port 52 is open, as in conventional two-cycle engines in 45 which the movement of pistons controls the opening and closing of the port, in the present case the intake port is not open before bottom dead center position is reached as in conventional types of two-cycle engines and is only opened after the exhaust port has been uncovered for a material time element. Further, because of the fact that the intake port 116 extends axially outwardly beyond the outer end of the exhaust port 52, the exhaust port closes while the intake port 50 is still substantially fully open. By this arrangement, the possibility of the loss of live gases through the exhaust port at lower engine speeds is substantially eliminated and, additionally, it provides a construction in which a positive super- 60 charging effect may be obtained.

It will be appreciated from the foregoing description that the engine provided in accordance with the present invention dispenses with base compression for delivering air for supporting the 65 combustible charge to the engine cylinder, and that this not only permits a more conventional, efficient and economical oiling system of the type commonly employed in connection with four-cycle engines to be employed therewith, but additionally in delivering such air positively to the power cylinder of the engine overcomes the loading effects of conventional types of two-cycle engines when run at low speed, and gives much better control of the engine at such low speeds. Furthermore, by introducing the air for support-

ing combustion in the power cylinder into the power cylinder under a relatively high pressure as described, better scavenging of the burnt parts of the combustion from the power cylinder obtained, operating conditions are materially improved, fuel economy at lower speeds is materially increased and a positive supercharging effect may be provided if desired, thus providing for a materially greater power output for the same cubic contents of the cylinders at a given speed.

Having thus described my invention, what I claim by Letters Patent is:

1. In a two-cycle engine of the class wherein a differential piston works in a differential cylinder and the smaller diameter portion of said piston controls the escape of exhaust gases through a port in the wall of said cylinder, an inlet port in the wall of the smaller diameter portion of said cylinder covered and uncovered by movement of said piston in said cylinder, air for supporting combustion being drawn into the larger diameter portion of said cylinder during movement of said piston toward bottom dead center position and compressed by said larger diameter portion during movement thereof toward top dead center position, a discharge passage from said larger diameter portion of said cylinder leading to said inlet port, and a rotary valve driven in timed relation to said engine interposed in said discharged passage, the combination with said valve of a pocket formed interiorly thereof and a port therein alternately communicating with that portion of said discharge passage leading thereto from said larger diameter portion of said cylinder and that portion of said discharge passage leading therefrom to said inlet port, the rotary position of said valve closing said port therein to both portions of said passage during substantially the entire power stroke of said piston whereby to hold said air compressed in said pocket during such time, and said valve moving to open said port to that portion of said passage leading to said inlet port during the initial movement of said piston from bottom dead center position toward top dead center position without opening communication between said pocket and that portion of said passage leading to said larger diameter portion of said cylinder.
2. In a two-cycle engine of the class wherein a differential piston works in a differential cylinder and the smaller diameter portion of said piston controls the escape of exhaust gases through a port in the wall of said cylinder, an inlet port in the wall of the smaller diameter portion of said cylinder covered and uncovered by movement of said piston in said cylinder, air for supporting combustion being drawn into the larger diameter portion of said cylinder during movement of said piston toward bottom dead center position and is compressed by said larger diameter portion during movement thereof toward top dead center position, a discharge passage from said larger diameter portion of said cylinder leading to said inlet port, and a rotary valve driven in timed relation to said engine interposed in said discharged passage, the combination with said valve of a pocket formed interiorly thereof and a port therein alternately communicating with that portion of said discharge passage leading thereto from said larger diameter portion of said cylinder and that portion of said discharge passage leading therefrom to said inlet port, the rotary position of said valve closing said port therein to both portions of said passage during substantially the entire power stroke of said piston whereby to hold said air compressed in said pocket during such time, said valve moving to open said port to that portion of said passage leading to said inlet port during the initial movement of said piston from bottom dead center position toward top dead center position without opening communication between said pocket and that portion of said passage leading to said larger diameter portion of said cylinder, and said communication between said pocket and said smaller diameter portion of said cylinder through said inlet port continuing after the last mentioned movement of said piston has closed the first mentioned port.
3. In a two-cycle engine of the class wherein a differential piston works in a differential cylinder and the smaller diameter portion of said piston controls the escape of exhaust gases through a port in the wall of said cylinder, an inlet port in the wall of the smaller diameter portion of said cylinder covered and uncovered by movement of said piston in said cylinder, air for supporting combustion being drawn into the larger diameter portion of said cylinder during movement of said piston toward bottom dead center position and compressed by said larger diameter portion during movement thereof toward top dead center position, a discharge passage from said larger diameter portion of said cylinder leading to said inlet port, and a rotary valve driven in timed relation to said engine interposed in said discharged passage, the combination with said valve of a pocket formed interiorly thereof and a port therein alternately communicating with that portion of said discharge passage leading thereto from said larger diameter portion of said cylinder and that portion of said discharge passage leading therefrom to said inlet port, the rotary position of said valve closing said port therein to both portions of said passage during substantially the entire power stroke of said piston whereby to hold said air compressed in said pocket during such time, said valve moving to open said port to that portion of said passage leading to said inlet port during the initial movement of said piston from bottom dead center position toward top dead center position without opening communication between said pocket and that portion of said passage leading to said larger diameter portion of said cylinder, and said communication between said pocket and said smaller diameter portion of said cylinder through said inlet port continuing after the last mentioned movement of said piston has closed the first mentioned port.
4. In a two-cycle engine of the class wherein a piston working in a cylinder controls the escape of exhaust gases through a port in the cylinder wall, a port in the cylinder wall covered and uncovered by movement of the piston is provided for the introduction of combustion supporting air to the cylinder, the piston being connected to a crankshaft by means of a connecting rod for converting reciprocatory movement of the piston to rotary movement of said crankshaft, and means provided for compressing said air for delivery through said last mentioned port, of means operated in timed relation to said engine for rendering said last mentioned port inoperative to deliver said compressed air to said cylinder until said piston has uncovered the first mentioned port and has substantially reached bottom dead center position, comprising a rotary valve interposed in the path of flow of said compressed air to said last mentioned port, said valve having a pair of diametrically opposed ports therein

entire power stroke of said piston whereby to hold said air compressed in said pocket during such time, said valve moving to open said port to that portion of said passage leading to said inlet port during the initial movement of said piston from bottom dead center position toward top dead center position without opening communication between said pocket and that portion of said passage leading to said larger diameter portion of said cylinder, and movement of said piston in said cylinder serving to interrupt communication between said pocket and said inlet port during the last mentioned movement of said piston.

5. In a two-cycle engine of the class wherein a differential piston works in a differential cylinder and the smaller diameter portion of said piston controls the escape of exhaust gases through a port in the wall of said cylinder, an inlet port in the wall of the smaller diameter portion of said cylinder covered and uncovered by movement of said piston in said cylinder, air for supporting combustion being drawn into the larger diameter portion of said cylinder during movement of said piston toward bottom dead center position and compressed by said larger diameter portion during movement thereof toward top dead center position, a discharge passage from said larger diameter portion of said cylinder leading to said inlet port, and a rotary valve driven in timed relation to said engine interposed in said discharged passage, the combination with said valve of a pocket formed interiorly thereof and a port therein alternately communicating with that portion of said discharge passage leading thereto from said larger diameter portion of said cylinder and that portion of said discharge passage leading therefrom to said inlet port, the rotary position of said valve closing said port therein to both portions of said passage during substantially the entire power stroke of said piston whereby to hold said air compressed in said pocket during such time, said valve moving to open said port to that portion of said passage leading to said inlet port during the initial movement of said piston from bottom dead center position toward top dead center position without opening communication between said pocket and that portion of said passage leading to said larger diameter portion of said cylinder, and said communication between said pocket and said smaller diameter portion of said cylinder through said inlet port continuing after the last mentioned movement of said piston has closed the first mentioned port.

10. In a two-cycle engine of the class wherein a piston working in a cylinder controls the escape of exhaust gases through a port in the cylinder wall, a port in the cylinder wall covered and uncovered by movement of the piston is provided for the introduction of combustion supporting air to the cylinder, the piston being connected to a crankshaft by means of a connecting rod for converting reciprocatory movement of the piston to rotary movement of said crankshaft, and means provided for compressing said air for delivery through said last mentioned port, of means operated in timed relation to said engine for rendering said last mentioned port inoperative to deliver said compressed air to said cylinder until said piston has uncovered the first mentioned port and has substantially reached bottom dead center position, comprising a rotary valve interposed in the path of flow of said compressed air to said last mentioned port, said valve having a pair of diametrically opposed ports therein

13

alternately operative to permit said flow of said compressed air therethrough to said last mentioned port during rotation of said valve, and means operatively interconnecting said valve to said crankshaft for receiving driving movement therefrom operable to drive said valve at one half the speed of rotation of said crankshaft.

5. In an internal combustion engine of the class including a cylinder, a piston reciprocable in said cylinder, a crankshaft and a connecting rod interconnecting said crankshaft and piston, the combination with said engine of means driven thereby for compressing a charge of combustion supporting air, said engine having a passage between said means and said cylinder, a rotary valve driven by said engine in timed relation therewith interposed in said passage, said valve having a pocket therein and a pair of ports communicating said pocket with the peripheral surface of said valve, one of said ports being aligned with that portion of said passage extending from said means to said valve during one portion of one revolution of said crankshaft at which time the other of said ports is not aligned with that portion of said passage leading to said cylinder, and said other of said ports being aligned

14

with that portion of said passage extending from said valve to said cylinder during a different portion of said revolution of said crankshaft at which time said one of said ports is not aligned with the first mentioned portion of said passage.
